UNITED STATES PATENT OFFICE

173,003

PLANTER

Bernard Yellin, Chicago, Ill., assignor to Bernard Edward Co., Chicago, Ill., a corporation of Illinois

Application March 22, 1954, Serial No. 29,642

Term of patent 7 years

(Cl. D35—3)

To all whom it may concern:

Be it known that I, Bernard Yellin, a citizen of the United States and a resident of the city of Chicago, county of Cook, State of Illinois, have invented a new, original, and ornamental Design for a Planter, of which the following is a specification, reference being had to the accompanying drawing, forming a part thereof, in which:

I claim:
The ornamental design for a planter, substantially as shown.
